UNITED STATES PATENT OFFICE.

JOHN H. WRAY, OF DANVILLE, PENNSYLVANIA, ASSIGNOR OF ONE-HALF TO
SHARPLESS M. DIETZ, OF SAME PLACE.

DESIGN FOR A KNIFE.

SPECIFICATION forming part of Design No. 34,897, dated August 6, 1901.

Application filed July 10, 1901. Serial No. 67,796. Term of patent 7 years.

To all whom it may concern:

Be it known that I, JOHN H. WRAY, a citizen of the United States, and a resident of Danville, in the county of Montour and State of Pennsylvania, have invented and produced a new and original Design for a Knife, of which the following is a specification, reference being had to the accompanying drawing, forming a part thereof, which represents a perspective view of a knife embodying my design.

The design presents the handle member *a*, from which projects longitudinally and thence laterally the tang *b*, such tang termi-

nating in a curved blade *c*, joined to the tang at the middle part of the blade.

Having described my invention, what I claim as new, and desire to secure by Letters Patent, is—

The design for a knife, as herein shown and described.

In testimony whereof I have signed my name to this specification in the presence of two subscribing witnesses.

JOHN H. WRAY.
